WINDOW FRAME FASTENING MEANS

Harry W. Cook, Malta, Ohio

Application December 24, 1936, Serial No. 117,556

6 Claims. (Cl. 20—12)

This invention relates to bonding devices for use in window frames especially such as are now constructed of wood.

As well understood such frames include a sill and two upright jambs or pulley stiles nailed near their lower ends to the oposite ends of the body of the sill. The sill, of course, is exposed to the weather and receives much rain and snow or ice. Owing to this exposure the sill and jambs or stiles become separated notwithstanding the nails customarily used and as a consequence permitting rain water or the water of melting snow or ice to pass in through the joints and perhaps resulting in the rotting of the sill and jambs or stiles unless seasonably attended to. But by reason of the position of those joints and the trim they are concealed and continue unobserved.

The principal object of the present invention is to provide a simple and economical means whereby the jambs are restrained from separation and held firmly to the ends of the sill irrespective of whether they are nailed together.

The invention is embodied in the example herein shown and described, the features of novelty being finally claimed.

In the accompanying drawings—

Figure 1 illustrates in front elevation, with parts broken out, a window frame in which the invention may be incorporated.

Fig. 2 is a perspective view, on a larger scale, of the restraining attachment according to the invention.

Fig. 3 is a fractional end elevation on the scale of Fig. 1, broken out, illustrating the attachment as applied thereto.

Fig. 4 is a fractional view, on the scale of Fig. 2, looking at the lower end of what is shown in Fig. 3.

Fig. 5 is a perspective view of the left hand (looking inward) lower corner of the window frame illustrating my invention applied thereto.

In the views 10 designates one of the side jambs of a window frame having a window stop seat 10^a. 11 designates the sill having a horn 11^a. 12 designates the head jamb having a stop seat 12^a coinciding with the window stop seat 10^a. The two side jambs are commonly nailed, as indicated at 13, to the opposite ends of the sill with the sill horns projecting beyond the jamb. The lower ends of the jambs are indicated as cut to coincide with the lower face of the sill but this is not necessary. The vertical members 14 and the horizontal member 15 constitute the usual external casings of the frame, the vertical members 55 resting at their lower ends on the horns of the

sill, and the horizontal member 15 resting on and joined to the upper ends of the vertical casing member.

My device for effecting or restraining the connection between the lower ends of the side jambs and the ends of the sills, as shown in Fig. 2, consists of a piece of rather stout wire or metal rod bent to form two arms 16 and 17 extending from an intermediate looped portion 18. The arm 16 is bent to form a driving shoulder 16^a from which 10 extends the spike member 16^b, and the arm 17 is bent from the loop portion 18 outwardly and thence downward at a right angle, as shown at the portion 17^a, and finally in a direction parallel to the extension of the loop portion and having 15 its end formed as a spike member 17^b, thereby producing a frame open at one side. The spike portions of the device are preferably formed broad like chisel ends, as shown, so that when driven into the wood of the parts engaged they stand 20 cross-wise of the grain of the wood and better resist movement in the wood.

In applying my device the spike end 16^b is first driven into the horn 11^a on the sill, the device being tilted slightly upward, as illustrated in 25 broken lines Fig. 4, and the blows of a hammer applied to said shoulder 16^a until said shoulder contacts with the wood of the sill horn, as depicted by the full lines Fig. 4, with the shoulder fitting snugly against the sill horn. After this 30 operation the restraining device is pressed or sprung down against the side jamb and the spiked end portion 17^b driven into the lower side of the sill, in which case the portion 17^a will lie against the lower side of the sill as indicated in Figs. 3 35 and 4. Finally a nail or screw 19 is driven through the loop 18 into the wood of the side jamb thereby cooperating with the spike ends referred to to hold the device in position. The devices are made as rights and lefts.

From the construction shown it will be observed that because the restraining device engages the sill at two points and embraces the side jamb said jamb is restrained from separation from the end of the sill with greater certainty than would be the case with nails as customarily used. The function of the fastening member 19 further strengthens the two connections referred to.

In the claims I use the word "jamb" to include 50 also what is called a pulley stile.

The forms of the parts can be changed without departing from the gist of the invention as claimed.

What I claim is:

1. A frame fastening means consisting of a wire or rod bent to form an arm of considerable length and a second arm bent to form a substantially rectangular frame open at one side, the said rectangular frame standing at a substantial angle to said first mentioned arm and with its open side adjacent a plane that coincides with the axis of the first mentioned arm and also intersects the plane of the said rectangular frame, 5 the free ends of said arms being connectible with the frame to be fastened.
2. A frame fastening means consisting of a wire or rod bent to form an arm of considerable length and having therein a bent portion forming a driving shoulder, and a second arm bent to form a substantially rectangular frame open at one side and standing in a plane at a substantial angle to said first mentioned arm, with said open side adjacent a plane that coincides with the axis 10 of the first mentioned arm and is substantially parallel to that side of the rectangular frame opposite said open side.
3. A frame fastening means consisting of a wire or rod bent to form an arm of considerable length and a second arm bent to form a substantially rectangular frame open at one side and standing in a plane at a substantial angle to said first mentioned arm, with its open side adjacent a plane that coincides with the axis of the first 15 mentioned arm and intersects the plane of the said rectangular frame, the ends of the said arms being sharpened in wedge form extending in planes substantially parallel to each other.
4. A frame fastening device consisting of a wire or rod bent to form an arm of considerable length and a second arm bent to form a substantially 20 rectangular frame open at one side and standing in a plane at a substantial angle to said first mentioned arm, with its open side adjacent a plane that coincides with the axis of the first mentioned arm and intersects the plane of the said rectangular frame, the free ends of said arms being connectible with the frame to be fastened.
5. In a window frame of wood, a bonding device for restraining the separation of the sill and a contiguous jamb consisting of a wire or rod bent to form an arm of considerable length having therein a driving shoulder, and a second arm bent to form a substantially rectangular frame 25 open at one side that stands in a plane at a substantial angle to said first mentioned arm with the said open side adjacent a plane that coincides with the axis of the first mentioned arm and intersects the plane of said rectangular frame, 30 the end portions of said arms engaging the sill at opposite sides of the contiguous jamb and with the said rectangular frame extended around the end of the said jamb.
6. A frame fastening device consisting of a wire or rod bent to form an arm substantially rectilinear for a considerable portion of its length and a second arm bent to form a substantially rectangular frame open at one side, said second mentioned arm standing in a plane substantially at a right angle to the direction of the 35 said length of the first mentioned arm, the ends of said arms adapted to engage the members to be fastened.

HARRY W. COOK.
